CLOSURE FASTENING DEVICE

James T. F. Butler, Takoma Park, Md.

Application March 28, 1956, Serial No. 574,457

5 Claims. (Cl. 292—296)

My invention relates broadly to closure fasteners and more particularly to a ratchet operated clamping device for sliding or swinging closures.

One of the objects of my invention is to provide a compact construction of closure device which may be readily inserted into position between two parts which are to be fastened and the parts clamped by the adjustment of a slidable device with respect to a ratchet.

Another object of my invention is to provide a ratchet controlled adjustable clamping device which may be inserted between a latch and the associated locking recess in a door and door jamb and a clamp thrust into adjusted position for maintaining the door in a closed position with respect to the associated jamb where the clamp is movable along a foldable guide forming part of the latching device.

Still another object of my invention is to provide a construction of foldable guide for a closure fastener device formed by a pair of hingedly connected sections where one of the sections serves as a carrier for a clamping device in stored or retracted position, while the other of the sections serves as an insertion and ratchet device for effecting an adjustable clamping operation of the parts to be secured.

Other and further objects of my invention reside in a resilient mechanism attached to a closure fastener and engageable with the recess of a latching device as set forth more fully in the specification hereinafter following by reference to the accompanying drawings, in which:

Figure 1 is a top plan view of the closure fastener of my invention shown in position for fastening a swinging door, the view illustrating certain of the associated parts in transverse section, and showing particularly the slideable clamp moved to a position out of the path of the swinging door;

Fig. 2 is a view similar to the view illustrated in Fig. 1 but showing the adjustable clamping device moved to clamping position with respect to the parts of a door;

Fig. 3 is an elevational view illustrating the coaction of the clamp with a door in closed position;

Fig. 4 illustrates in longitudinal section the parts of the closure fastener illustrated in Fig. 2;

Fig. 5 shows the closure fastener with the guide for receiving the clamping device moved into the ratchet portion of the clamping device;

Fig. 6 is an enlarged transverse sectional view showing the manner in which the closure fastener of my invention may be inserted in the mortise of a door jamb to enable the door to be fastened with respect to the door jamb;

Fig. 7 is a vertical sectional view taken substantially on line 7—7 of Fig. 6;

Fig. 8 is a view looking at the rear of the portion of the closure fastener that is insertable between the door and the door jamb and illustrating particularly the adjustable spring which engages the mortise or recess in the door jamb;

Fig. 9 is a perspective view of the resilient device carried by the insertable portion of the fastener of my invention.

2

tion and which is adapted to adjustably engage the mortise or recess in the door jamb;

Fig. 10 is a view similar to the view illustrated in Fig. 6, but showing the application of the device of my invention to a door wherein the mortise or recess in the door jamb is substantially smaller than the mortise or recess in the door jamb illustrated in Fig. 6;

Fig. 11 is an elevational view of a closure fastener device embodying my invention but illustrating a modified form of resilient device for engaging the mortise or recess in the jamb of a door to be fastened;

Fig. 12 is a top plan view of the form of my invention shown in Fig. 11;

Fig. 13 is a transverse sectional view taken through the reciprocative member on line 13—13 of Fig. 11, the view being shown on an enlarged scale;

Fig. 14 is a fragmentary view on an enlarged scale illustrating the limit stop which I provide for the reciprocative member in the form of my invention shown in Figs. 11—13;

Fig. 15 is a fragmentary front elevational view on an enlarged scale showing the manner of pivotally mounting the swinging part of the device in the flat plate of the device; and

Fig. 16 is a fragmentary plan view on an enlarged scale of the structure shown in Fig. 15.

My invention is directed to a ratchet type lock for fastening two relatively movable parts. I have illustrated my invention as particularly applicable to a ratchet door lock but it will be understood that other applications of the device will readily suggest themselves. The ratchet door lock of my invention consists of a pair of flat hinged metallic members where the members may be moved to coplanar position or folded to a relatively compact position. A pawl controlled slide is provided which is movable over the two parts of the device when the parts are in coplanar alignment and which may be stowed out of obstructing position on one part of the hinged device or which may be adjusted in coaction with a ratchet on the other part of the device for fastening the door in closed position with respect to a coacting door jamb. The part of the device which is ratched for the adjustment of the slide also carries a resilient device engageable in the latch recess or mortise in the door jamb. The resilient device may have many forms, either in the nature of the spring wire assembly or the reciprocative device shown in the drawings, or other forms of engagement means within the scope of the appended claims hereinafter following.

I have found the ratchet door lock of my invention particularly effective in fastening a door from the inside for preventing entry. The device is readily portable and is foldable into a compact package for transportation and application to various types of doors or other relatively movable closures.

Referring to the drawings in more detail, reference character 1 designates a fixed door jamb while reference character 2 shows a coacting hinged door swingable from the position illustrated in Fig. 1 to the position illustrated in Fig. 2, the door including the conventional reciprocative latch represented at 2a. The door jamb 1 is provided with the conventional latch recess or mortise 3. This recess or mortise 3 may be of various sizes in different doors as indicated in the comparative Figs. 6 and 10, for example, where the recess or mortise 3 in the door jamb 1 of Fig. 6 has substantial transverse width, whereas the comparable recess or mortise in the door jamb 1' of Fig. 10 has substantially less transverse width designated at 3' in Fig. 10. I mention this to emphasize the fact that the device of my invention has been developed to meet a wide variety of conditions which may be encountered in various types of door installations. It is usual

that the recess or mortise 3 or 3' is covered by a marginal frame member 4 shown in Fig. 6, or 4' shown in Fig. 10. The frame member 4 or 4' contains a rectangular recess 5 or 5', respectively within which the conventional latch carried by the door 1 normally engages. In lieu of this latch engagement, however, I provide the locking device of my invention which consists of the two hinged parts 6 and 7 hingedly connected at 8. The part 6 is pressed from a strip of flat sheet metal and has an outstruck lug 9 projecting therefrom in a plane normal to the plane of the flat strip 6 and adapted to be inserted in the rectangular recess 5 or 5' (Figs. 6 and 10) of the frame 4 or 4' and into the mortise or recess 3 or 3'. The lug 9 is struck from the material of the strip 6 leaving an open central path 10 in the end of the strip 6. That is the strip 6 is bifurcated on the end thereof, the two parts of the bifurcation being indicated at 11 and 12 in Fig. 8. The bifurcation carries either the resilient wire device which I have shown in Figs. 1-10 or the reciprocal device shown in Figs. 11 and 14. The resilient wire device of Figs. 1-10 is shown in perspective view in Fig. 9 and consists of a pair of resilient wire side members 14 and 15 having intermediate resilient coils 16 and 17 therein. The ends of the wire side members at 18 and 19 extend into apertures provided in plate 6 and form fastening means between the resilient wire assembly and the plate 6. The opposite end of the resilient wire assembly is formed as shown in Fig. 9 where the side portions 14 and 15 of the wire assembly are interconnected by the transversely extending portion 20 having re-entrant bends 21 and 22 connected therewith which enable the displaceable end of the wire assembly to slidably engage the inwardly directed edges of the bifurcations 11 and 12. The wire side members 14 and 15 connect to the re-entrant bends 21 and 22 through the offset portions 23 and 24. The offset portions 23 and 24 of the wire side members 14 and 15 form notches in the wire side members which engage over the edge 25 of frame 4 in Fig. 6, or edge 25' of frame 4' in Fig. 10. In order to adapt the plate 6 to door jambs having recesses or mortises 3 or 3' (Figs. 6 and 10) of different transverse widths the resilient wire assembly is simply forced into the frame 4 or 4' of the recess or mortise in the door jamb, resulting in the vice-like compression of the resilient wire assembly where the re-entrant bends 21 and 22 slide on the inner edges of bifurcations 11 and 12 and offset portions 23 and 24 snap into engagement with the edge of the frame 4 or 4' at 25 or 25' where the lug 9 serves as a limiting means for positioning the plate 6 with respect to the opposite edge of the frame 4 or 4' as shown in Figs. 6 and 7.

The hinged part 7 which connects through hinged connection 8 with the hinged part 6 consists of a wire frame pivoted at its ends at 26 and 27 in the end of plate 6, and is provided with a finger-engaging portion 28 at its opposite end. The substantially parallel sides of the wire frame 7 abut with projections 6a on plate 6 as shown more clearly in Figs. 15 and 16, which limit the movement of hinged part 7 in one direction beyond a coplanar position as illustrated in Fig. 5, although is free to move in the opposite direction as illustrated in Figs. 1-4. The part 7 is movable from the coplanar position shown in Fig. 5 limited by the abutment stops 6a on plate 6 to a position within the limits of an acute angle with respect to the plane of part 6 as shown in Figs. 2 and 4. The finger-engaging portion 28 in one end of the hinged part 7 is connected through a chain 29 through a fixed connection 30 on the door jamb for maintaining the device in position with respect to the door when the device is permanently applied to any particular door. Otherwise, the device may be simply carried in a purse as a portable device and used to fasten any door or other closure on the inside against entry from the outside.

The plate 6 is provided with vertically extending 75

ratchet teeth which I have indicated at 31. These ratchet teeth are disposed transversely of the plate 6 and are closely spaced permitting close adjustment of the slide 32 which is engageable over the hinged parts 6 and 7. 5 The slide 32 carries a pawl 33 pivotally mounted on transverse bar 34 carried by the lugs 35 struck from the material of the slide 32. The pawl 33 is provided with teeth 36 which engage the ratchet teeth 31 on plate 6. A coil spring 37 interposed between one of the lugs 35 and the pawl 33 serves to bias pawl 33 in a position where the teeth 36 thereon tend to engage the ratchet teeth 31 on plate 6. A finger actuator 38 on pawl 33 may be depressed to release the teeth 36 from engagement with the ratchet teeth 31. The slide 32 carries a pressure plate 39 extending in a plane normal to the axis of the slide 32 and which engages the face of the door 2 as shown more clearly in Figs. 2-5. By forcing the pressure plate 39 against the face of the door 2 when the device is inserted in the position illustrated in Figs. 2-5 the door 2 may be confined in position with respect to the door jamb 1. By reason of the fine adjustment permitted because of the close linear pitch of the ratchet teeth 31 on plate 6 and the teeth 36 on pawl 33 a very precise adjustment of pressure plate 39 against door 2 may be obtained.

When the device is not in use the device may be maintained in position illustrated in Fig. 1, with the plate 6 resiliently engaged in the recess or mortise in the door jamb 1 and the slide 32 stowed on the hinged part 7, or the device may simply be hung from the chain 29 fastened to the fixed connection 30. In any event the assembly is most compact. When, however, the device is placed in use the slide 32 must be transferred from the stowed position shown in Fig. 1 to the fastening position illustrated in Figs. 2 and 4. This is accomplished by moving the hinged part 7 to a position coplanar with plate 6 as shown in Fig. 5, whereupon slide 32 may be transferred from the stowed portion on hinged part 7 to the fastening position on hinged part 6. The pressure plate 39 is then forced against door 2 and the teeth 36 of pawl 33 engaged in the selected ratchet teeth 31 in plate 6 thereby maintaining a reliable closure of door 2 without any necessity of a key at all. Pawl 33 is manipulated by pressing spring biased finger actuator 38 to enable the slide 32 to be moved to the desired adjusted position or 40 the pressure exerted by pressure plate 39 relieved and withdrawn for restoring the slide 32 to the stowed position as shown at 31.

In the operation of the device of my invention the plate 6 forms a cam surface against which the conventional reciprocal latch 2a in the door 2 moves and is retracted from the position illustrated in Fig. 1 to the position illustrated in Figs. 2, 4 and 5. Under these conditions a key for the conventional lock is unnecessary and the securing of the door is achieved by forcing the pressure plate 39 against the door with the plate 6 secured in position in the door jamb as shown in Figs. 2 and 4.

In lieu of the resilient wire assembly shown in Figs. 1-10, I may employ the reciprocal device shown in Figs. 11-14 consisting of the block 40 which is curved on its exterior face and which is provided with linearly extending lugs 41 and 42 on opposite sides thereof which slide in a confined path along grooves in the inner edges of bifurcations 11 and 12. The lug 9 serves not only as an entry member for entering the recess or mortise 3 in the jamb 1 of the door but also as a confining means for the coil spring 43 which bears against the block 40 urging the block 40 to its limit of movement restricted by the strip 44 which is fastened across the bifurcated ends 11 and 12 of plate 6. The block 40 is free to be displaced against the action of coil spring 43 to a position in which it may readily engage the recess or mortise 3 through the rectangular recess 5 in frame 4 of the door jamb. By reason of the fact that the block 40 is readily

displaceable the device may be secured in recesses or mortises of various sizes as explained in connection with the resilient wire assembly in the form of my invention in Figs. 1-10. The curved surface 40a of block 40 insures a cam-like slidable entry into and out of the rectangular recess 5 in frame 4 of the recess or mortise 3.

I have found the device of my invention highly practical and successful in use, and while I have described my invention in certain of its preferred embodiments I realize that modifications may be made, and I desire that it be understood that no limitations upon my invention are intended other than may be imposed by the scope of the appended claims.

What I claim as new and desire to secure by Letters Patent of the United States is as follows:

1. A closure fastener for securing a movable member with respect to a fixed member comprising a pair of pivotally connected parts, means on one of said parts for engaging the fixed member, the other of said parts being movable from a position coplanar with the aforesaid part to a position at an acute angle with respect thereto, a slide carrying a pressure plate engageable with the movable member, said slide having a transverse section which envelopes the transverse section of said part which engages the fixed member and being shiftable in positions selectively enveloping each of said parts when said parts are aligned in coplanar position, said slide being stowable in a position transversely enveloping one of said parts and the said part with the slide stowed thereon being swingable about the pivot on said first mentioned part to a position at an acute angle with respect to the plane of said first mentioned part and means on said first mentioned part for selectively maintaining the position of said slide and the pressure plate thereon with respect to the movable member and in which said first mentioned part is provided with a pair of transversely spaced longitudinally extending abutment stops thereon projecting beyond the end of said first mentioned part at one side of the path of movement of said other part for resisting the movement of said last mentioned part to a position coplanar with said first mentioned part.

2. A closure fastener for securing a movable member with respect to a fixed member comprising a pair of pivotally connected parts, means on one of said parts for engaging the fixed member, the other of said parts being movable from a position coplanar with the aforesaid part to a position at an acute angle with respect thereto, a slide carrying a pressure plate engageable with the movable member, said slide having a transverse section which envelopes the transverse section of said part which engages the fixed member and being shiftable in positions selectively enveloping each of said parts when said parts are aligned in coplanar position, said slide being stowable in a position transversely enveloping one of said parts and the said part with the slide stowed thereon being swingable about the pivot on said first mentioned part to a position at an acute angle with respect to the plane of said first mentioned part and means on said first mentioned part for selectively maintaining the position of said slide and the pressure plate thereon with respect to the movable member and in which the means on said first mentioned part for engaging the fixed member comprises a resilient wire assembly consisting of a pair of resilient wire side members, said wire side members projecting beyond the plane of said first mentioned part and engageable with the fixed member, said wire side members being interconnected adjacent the plane of the first mentioned member and being yieldably displaceable at the plane of said first mentioned part.

3. A closure fastener for securing a movable member with respect to a fixed member comprising a pair of pivotally connected parts, means on one of said parts for engaging the fixed member, the other of said parts being movable from a position coplanar with the aforesaid part to a position at an acute angle with respect thereto, a

slide carrying a pressure plate engageable with the movable member, said slide having a transverse section which envelopes the transverse section of said part which engages the fixed member and being shiftable in positions selectively enveloping each of said parts when said parts are aligned in coplanar position, said slide being stowable in a position transversely enveloping one of said parts and the said part with the slide stowed thereon being swingable about the pivot on said first mentioned part to a position at an acute angle with respect to the plane of said first mentioned part and means on said first mentioned part for selectively maintaining the position of said slide and the pressure plate thereon with respect to the movable member and in which the means on said part for engaging the fixed member comprises a lug connected with said first mentioned part and projectable into the fixed member and a substantially V-shaped resilient wire assembly carried by said first mentioned part and displaceable toward and away from said lug for maintaining said first mentioned part in engagement with the fixed member.

4. A closure fastener for securing a movable member with respect to a fixed member comprising a pair of pivotally connected parts, means on one of said parts for engaging the fixed member, the other of said parts being movable from a position coplanar with the aforesaid part to a position at an acute angle with respect thereto, a slide carrying a pressure plate engageable with the movable member, said slide having a transverse section which envelopes the transverse section of said part which engages the fixed member and being shiftable in positions selectively enveloping each of said parts when said parts are aligned in coplanar position, said slide being stowable in a position transversely enveloping one of said parts and the said part with the slide stowed thereon being swingable about the pivot on said first mentioned part to a position at an acute angle with respect to the plane of said first mentioned part and means on said first mentioned part for selectively maintaining the position of said slide and the pressure plate thereon with respect to the movable member and in which said first mentioned part is bifurcated and in which said means for engaging said fixed member includes a lug projecting from said first mentioned part at the bight portion of said bifurcation, and yieldable means mounted on the face of said first mentioned part and movable longitudinally of said bifurcation toward and away from said lug, said fixed member having a recess therein, said lug engaging one side of said recess and said yieldable means resiliently engaging the other side of said recess in the fixed member.

5. A closure fastener for securing a movable member with respect to a fixed member comprising a pair of pivotally connected parts, means on one of said parts for engaging the fixed member, the other of said parts being movable from a position coplanar with the aforesaid part to a position at an acute angle with respect thereto, a slide carrying a pressure plate engageable with the movable member, said slide having a transverse section which envelopes the transverse section of said part which engages the fixed member and being shiftable in positions selectively enveloping each of said parts when said parts are aligned in coplanar position, said slide being stowable in a position transversely enveloping one of said parts and the said part with the slide stowed thereon being swingable about the pivot on said first mentioned part to a position at an acute angle with respect to the plane of said first mentioned part and means on said first mentioned part for selectively maintaining the position of said slide and the pressure plate thereon with respect to the movable member and in which said means on one of said parts for engaging the fixed member includes a resilient wire assembly having wire side members fixed at one end to said first mentioned part and slidably engaging said first mentioned part at the other end thereof,

said wire side members including convolutions therein in portions of said wire side members which project beyond the plane of said first mentioned part and offset portions in said wire side members disposed between the convolutions therein and the slideable portion thereof which engages the first mentioned part, said offset portions constituting notches engageable with a recess in the fixed member.
